H. H. TIMKEN.
CUP FOR ROLLER BEARINGS AND PROCESS OF MAKING SAME.
APPLICATION FILED JUNE 29, 1918.

1,326,225.

Patented Dec. 30, 1919.

UNITED STATES PATENT OFFICE.

HENRY H. TIMKEN, OF CANTON, OHIO.

CUP FOR ROLLER-BEARINGS AND PROCESS OF MAKING SAME.

1,326,225.

Specification of Letters Patent. Patented Dec. 30, 1919.

Application filed June 29, 1918. Serial No. 242,606.

To all whom it may concern:

Be it known that I, HENRY H. TIMKEN, a citizen of the United States, and a resident of the city of Canton, in the county of 5 Stark and State of Ohio, have invented a new and useful Improvement in Cups for Roller-Bearings and Processes of Making Same, of which the following is a specification.

10 My invention relates to a process of manufacturing cups for conical roller bearings, whereby much skilled work, much waste of material and much loss of product due to inaccuracies and distortions occasioned by heat 15 treatment or by insufficiently accurate workmanship are avoided.

The principal objects of the present invention are to simplify the process of manufacturing conical bearing cups, to reduce 20 the cost of manufacture, and to minimize the danger of distortion in the heat treatment.

In the accompanying drawing, which forms part of this specification, and wherein like symbols refer to like parts wherever 25 they occur,

Figure 1 is an end view of a cylindrical tube constituting the stock from which the bearing cup is formed;

Fig. 2 is a side view of the tube, with 30 dotted lines indicating where sections or rings are to be cut therefrom;

Fig. 3 is a side view of one of said sections or rings;

Fig. 4 is a vertical sectional view of the 35 die with the section or ring in initial position therein and with the punch shown in side elevation and in raised position;

Fig. 5 is a vertical sectional view through the die, punch, and cup or ring showing the 40 punch at the downward limit of its stroke;

Fig. 6 is a sectional view of a finished cup or ring of varying thickness;

Fig. 7 is a view of a blank for the cup in the form of a straight flat strip or ribbon;

45 Fig. 8 is a cross-section of a ring formed out of the blank shown in Fig. 7;

Fig. 9 is a view of a blank in the form of an arucate flat strip or ribbon; and

50 Fig. 10 is a cross-section of a ring made out of the blank illustrated in Fig. 9.

According to the present invention, it is preferable to start with a seamless tube A of drawn steel of cylindrical section. This tube is cut into short lengths or rings A¹ of approximately the length of the finished cup, or a little less. Both the inner and the outer

surfaces of this ring are made approximately cylindrical and concentric so as to have a wall of even thickness throughout. In order to obtain accuracy and concentricity of the inner surface at small expense, it is preferred to ream out the interior of the ring or short length of the tube to a diameter very slightly less than required and then simply finish the same by broaching in a press.

At this stage of manufacture, the ring A¹ is a cylinder; and the next operation is to convert this cylinder into a true conical cup with its inner and outer surfaces concentric. This result can be accomplished either by expansion or by contraction of the cylinder, the latter being preferred. For the purpose of contracting the cylinder into a cone, the cylindrical ring A¹ is forced endwise in a strong tapering die C whose operative inner surface 1 is of conical form and of a diameter which ranges from a little more than the overall diameter of the ring at the top of the die to the overall diameter of the finished cone at the bottom of the operative surface of the die, at which point the diameter of the die opening is abruptly decreased, thus forming a shoulder 4.

Mounted on or integral with the plunger 85 D, which applies the force to the end of the ring, is a mandrel 3 arranged in axial alignment with the die and whose exterior surface is a cone of the size and inclination of the interior of the finished cup. When the ring A¹ is placed in the die and pressure applied thereto by means of the plunger, the effect is to force the ring inwardly of the die. This operation contracts the diameter of so much of the ring as comes in contact with the inner surface of the die, so as to conform the outer surface of the ring to the inner surface of the die; and at the same time, the inner surface of the ring is made to conform to the outer face of the mandrel. The cup is loosened from the die by a suitable knock-out E.

The progressive movement of the ring inwardly of the die continues until it brings up against the shoulder; and its further forward movement being thus prevented, the continued pressure of the mandrel causes the metal to flow so as to fill all void space between the surface of the lower portion of the die and the corresponding surface of the mandrel. While the inner surface of the die and the outer surface of the mandrel

have a common axis, it is preferable that the inclination of the inner surface of the die should be less than the inclination of the outer surface of the mandrel; in which 5 case, the resulting cup A² must be thicker at its small end than at its large end. The surfaces of the cup A² are accurately enough finished by this die-shaping operation to make it unnecessary to do further work on 10 them before hardening or carbonizing. The inclination of the die is such that the outer surface of the cup will have a taper equal to the angle of repose of the cup metal for the metal with which the cup will be in contact 15 when in use; that is to say, the inclination of the outer surface is such that when the cup is in place there will be a tendency for it to jam into its retaining member rather than to loosen. In the case of cups 20 designed for use in motor vehicle axle bearings, the outer surface of the cups will have an inclination equal to the angle of repose of the cup metal for ordinary hub metal.

The next step is to carbonize the cones or 25 cups in the usual manner or submit them to any of the usual heat treatments for the purpose of hardening them. As these conical cups are of circular section, the tendency is for them to distort very little, if any, 30 during the heat treatment; and the form of the cup makes it a simple matter to correct minor irregularities arising from warping. Consequently, there is practically no loss of the product due to the heat treatment, and 35 very little, if any, occasion to grind the hardened surface. In other words, the grinding operation heretofore commonly required may be dispensed with entirely.

The principal advantage in contracting 40 the ring, rather than expanding it, is that the contraction avoids the severe tensile stress that might disrupt the wall. Besides, the operation of the contracting is better adapted for rectifying any unevenness in 45 the thickness of the wall and it tends to make the metal more compact.

While it is preferable to start with tubing, it is practicable to start with sheet metal. For this purpose, a blank may be made 50 in the form of a straight flat strip B having one end notched and the other end pointed conformably to the notch, as illustrated in Fig. 7, or the blank may be in the form of an arcuate strip F with one end notched 55 and the other end pointed to conform to said notch, as illustrated in Fig. 9. In the case of the flat strip, it is rolled into a cylindrical ring B¹ with its pointed end fitting into the socket end, as illustrated in Fig. 8; 60 and in the case of the arcuate strip, it is likewise rolled into the form of a conical ring F¹, as illustrated in Fig. 10. It is preferable to accurately finish both surfaces of the straight and arcuate strips before they 65 are rolled into the cylindrical rings. So

long as the ends of the sheet metal blanks are initially brought into contact or close proximity, they may be treated the same as the closed ring or section tubing, as hereinbefore described. During this treatment, the 70 enormous pressure to which they are subjected causes a circumferential strain that produces a perfect fitting of the ends so that, in the resulting product, the surface is almost as smooth and uninterrupted as if the 75 metal was continuous at the joint. One advantage of this feature is that the cup is enabled to spring under unusual conditions where a solid ring would be likely to fail. This rolled conical shell may be carbonized 80 before or after treatment in the tapered die and can be hardened after such treatment but the hardening process can be done in tapered dies with suitable flutings for admission of quenching fluid but having these 85 flutes of proper taper to hold the finished cup in close approximation to exact desired finished shape.

What I claim is:

1. The process of making conical cups for 90 roller bearings which consists in forming a ring with a cylindrical bore, finishing the inner surface of said ring and then die-shaping said ring into a conical cup of less diameter than said cylindrical bore by means of 95 a tapering mandrel whose inclination is greater than the inclination of said die.

2. The process of making conical cups for 100 roller bearings which consists in forming cylindrical rings of approximately even thickness, finishing the inner surface of said rings and then die-shaping said rings into conical cups with walls having an inside and outside surface approximately concentric but having said surfaces with different degrees of taper.

3. The process of making conical cups for 110 roller bearings which consists in forming a ring, reaming the bore thereof to a cylindrical surface and then forcing said ring endwise of a conical die by means of a conical mandrel concentric therewith but of greater inclination, whereby the inner surface of the cup acquires the proper inclination for a bearing surface for the rollers and the 115 outer surface of the cup acquires an inclination adapted to produce a wedging action of said cup in its mounting.

4. The process of making conical cups for 120 roller bearings which consists in finishing the surface of a strip of sheet metal, rolling said strip into the form of a ring and then die-shaping said ring into a conical cup.

5. The process of making conical cups for 125 roller bearings which consists in finishing the surface of an arcuate strip of sheet metal, rolling said strip into a ring and then die-shaping said ring into a conical cup.

6. The process of making conical cups for 130 roller bearings which consists in bending a

strip of sheet metal into a ring and forcing said ring with a conical mandrel endwise into a taper-die.

7. The process of making conical cups for roller bearings which consists in finishing the surface of a flat strip of sheet metal, bending said strip into a ring with the finished surface inside, forcing said ring with a mandrel of the inclination desired for the bearing surface of the cup into a taper-die of the lesser inclination desired for the outer surface of the cup, the pressure being sufficient to make the metal fill the annular space between the mandrel and the die.

8. A cup for a conical roller bearing comprising an inner bearing surface having an inclination suitable for coöperation with the bearing rollers and an outer bearing surface having an inclination less than its angle of repose for ordinary hub metal.

9. As a new article of manufacture, a conical cup for roller bearings resulting

from the contraction of a cylindrically reamed ring in a slightly tapered die by a taper mandrel of greater inclination with 25 pressure sufficient to make the metal completely fill the annular space between the mandrel and the die.

10. As a new article of manufacture, the cup for conical roller bearings resulting 30 from the operation of a conical mandrel on a strip of metal rolled into a ring in a taper-die under sufficient pressure to make the metal fill the space between the mandrel and the die.

11. A split cup for conical roller bearings resulting from the operation of a conical mandrel against a split ring in a conical die under pressure sufficient to make the metal fill the void space between the mandrel and 40 the die.

Signed at Canton, Ohio, this 25th day of June, 1918.

HENRY H. TIMKEN.
